Patented Mar. 7, 1922.

Inventor:
Prior F. Willis,

*By George A. Pennington
his Atty.*

UNITED STATES PATENT OFFICE.

PRIOR F. WILLIS, OF ST. LOUIS, MISSOURI.

TORCH.

1,408,673.

Specification of Letters Patent.

Patented Mar. 7, 1922.

Application filed November 23, 1918. Serial No. 263,896.

To all whom it may concern:

Be it known that I, PRIOR F. WILLIS, a citizen of the United States, residing in the city of St. Louis and State of Missouri, have invented a new and useful Improvement in Torches, of which the following is a specification.

This invention relates to gas burners or blow-pipes, more commonly referred to as torches and used for the fusing or welding and cutting of metal, and in the use of which some fuel gas, such as acetylene, hydrogen, coal product, or the like, with a supporter of combustion, such as oxygen, is employed.

In devices of this character the burner head is usually arranged and provided for the attachment of interchangeable nozzles or tips of various sizes and capacity, and, obviously, it is necessary to maintain leak-proof joints between the head and the nozzle or tip, so as to prevent the escape of the separate gases to the atmosphere and to secure the proper proportionate mixture of the gases for combustion.

As the nozzles or tips are usually made, however, the seating faces thereof are liable to injury or disfiguration, by being dropped upon the floor or other hard surface, to such an extent as to render them inefficient and even absolutely useless for the purpose intended.

The present invention therefore, has for its principal objects to produce a structure to obviate the above noted disadvantage, to simplify the structure of the burner as a whole, to particularly improve the means for attaching the nozzles or tips to the head, to eliminate shoulders or obstructions in the head on which dirt and grit might lodge, and to provide for the easy cleaning of the interior of the head. Other advantages to be attained will more fully appear from the following description.

The invention consists in a novel structure, and in the parts and combinations and arrangements of parts hereinafter set forth and afterwards pointed out with particularity in the appended claims.

In the accompanying drawing wherein

the invention is illustrated as applied to a fusing or welding torch,—

Figure 1 is a side elevation of the complete torch;

Figure 2 is a longitudinal section through the burner head with the tip in place;

Figure 3 is a detail view of the tip detached; and

Figure 4 is a longitudinal section through the burner head with the conducting pipes 60 and tip removed therefrom.

Referring now to the drawing, the numeral 1 designates the handle portion of the torch of the usual or any desirable construction, but having two separate passages 65 therethrough (not shown) and provided respectively with cut-off valves 2 and 3. Communicating with one of the passages, at one end of the handle, is a supply pipe 4 for the oxygen or supporter of combustion, while the other passage has a pipe 5 communicating therewith for supplying the acetylene or other suitable fuel gas. The opposite end of the handle 1 is connected to the burner head 6 by pipes 4^a and 5^a which 75 conduct the separate gases from the supply pipes.

As shown more clearly in Figures 2 and 4, the burner head 6 has a bore 7 therethrough, at the opposite ends of which are 80 tapered or flared seats 8, 9, respectively. The head is further provided with two gas passages, the one, 10, affording communication between the pipe 4^a and the middle cylindrical portion of the bore 7, and the 85 other, 11, affording communication between the pipe 5^a and the flared seat portion 9 of the bore.

The nozzle or tip, as shown, and designated generally by the numeral 12, is provided with the usual, relatively small, longitudinal bore or passage 13 for the outlet of the combustible gas mixture, and the transverse or oblique ports 14, 15, which respectively afford communication between the 95 bore 13 and the passages 10 and 11, as will presently appear.

The nozzle or tip 12 is provided with a counterpart tapered portion 16 to fit the seat portion 9 of the bore 7 in the head 6, 100

and with a shank portion, a part of which, as shown, is generally cylindrical, as at 17, so as to snugly fit the bore 7, while the balance thereof is reduced in diameter, as at 18, and screw-threaded, as at 19, to enter a threaded socket 19^a in a securing nut or plug 20 having a tapered portion 21 to fit the flared seat portion 8 of the bore 7.

When the nozzle or tip is in place as shown in Figure 2, there is an annular space 22 in the bore 7, about the part 18 of the shank, and between the shoulder formed by the part 17 and the end of the nut or plug 20. With this space 22 the gas passage 10 of the head 6 communicates, and to afford communication between said space 22 and the port 14 in the nozzle or tip, the part 17 of the shank is cut away or flattened on one side, as at 23; or, obviously, the shank may 20 be grooved longitudinally to afford the passageway to said port 14, of which latter there may be only one as shown, or more if desirable.

To afford ample communication between the gas passage 11 and the ports 15, of which latter there may be two as shown, or more or less, as desired or necessary, the tapered seating face of the nozzle or tip is grooved annularly, as at 24 (shown more clearly in Figure 3), said groove being located so as to register with the end of the passage 11 and having the ports 15 terminating therein.

By accurately forming the seating faces of the nozzle or tip and the burner head, a perfect seal is obtained to prevent leakage of the gases; and, obviously, these seating faces and the shank portions of several nozzles or tips of different working capacities may be made to one and the same standard for interchangeability, it being only necessary to vary the capacity of the mixing chambers, outlet passages and ports of the respective nozzles or tips.

The provision of the shank extension, in addition to affording a simple and efficient means for the attachment of the nozzle or tip to the burner head, further serves as a guard to prevent mutilation of the seating face 16. That is to say, if the nozzle or tip is placed or falls upon a plain flat surface, such as the floor, work table or the like, only the peripheral portion 25 of the enlargement adjacent to the seating face and the extreme end portion of the shank will touch said surface. This is a material advantage attained and one of the prime features of novelty in the invention.

A further advantage of the invention is the ease with which the bore 7 may be cleaned, due to the absence of any abrupt shoulder or obstruction for the lodgment of particles of grit or other foreign substance.

Obviously, the structure admits of con-

siderable modification without in the least departing from the spirit of the invention. Therefore, it is not limited to that shown in the drawing. It is further understood that the invention is equally applicable to a cutting torch as well as to the fusing or welding torch shown, the only difference being in the arrangement of the passageways in the nozzle or tip as is well known in the art.

What is claimed is:

1. In a torch of the character described, a head having a bore therethrough, the ends of the bore being flared outward, a detachable nozzle having a shank extending in said bore and having a counterpart tapered enlargement at the base of said shank fitting the adjacent flared portion of the bore with sealing effect, and a plug having an axial screw-threaded engagement with said shank of the nozzle and having a counterpart tapered portion fitting the adjacent flared portion of the bore of said head with sealing effect, said head having a gas passage communicating with said bore thereof between its flared portions and a separate gas passage communicating with the flared portion in which the enlargement of the nozzle at the base of its shank seats, said nozzle having a longitudinal mixing chamber with a port communicating with said bore of the head between the flared portions of the latter and a second port open through the seating face of the enlargement at the base of the shank of the nozzle, and an annular, grooved passageway being provided between said enlargement and the cooperating flared portion of the bore of the head affording communication with said second mentioned gas passage of the head in any rotative position of the nozzle in place.

2. In a torch of the character described, a head having an unrestricted bore therethrough, the ends of the bore being flared outward, said head having a gas passage communicating with said bore between the flared portions thereof and a second gas passage communicating with one of said flared portions, a nozzle having a shank extending in said bore of the head and having a counterpart tapered enlargement at the base of said shank fitting the tapered portion of the bore of the head with which said second mentioned gas passage communicates, and a plug having an axial screw-threaded engagement with the outer end portion of said shank of the nozzle and a counterpart tapered portion fitting the flared portion of the bore opposite the flared portion with which the tapered enlargement of the shank cooperates, said nozzle having a longitudinal mixing chamber with a port opening through the shank clear of the seating portion of the enlargement at the base of the shank and a second port opening through said enlargement, an annular, grooved pas-

sageway being provided between said shank and bore to afford communication between said first mentioned gas passage of the head and first mentioned port of the nozzle, and
5 an annular, grooved passageway being provided between said enlargement of the nozzle at the base of the shank and the co-operating flared portion of the bore af-

fording communication between said second mentioned gas passage of the head and said 10 second mentioned port of the nozzle.

In testimony whereof, I have hereunto set my hand, this 13th day of November, 1918, at St. Louis, Missouri.

PRIOR F. WILLIS.
